UNITED STATES PATENT OFFICE.

FREDERICK WESTERBECK, OF ST. LOUIS, MISSOURI.

SHEET-METAL DISPLAY BOX.

1,411,463.

Specification of Letters Patent. Patented Apr. 4, 1922.

Application filed June 27, 1919. Serial No. 307,164.

To all whom it may concern:

Be it known that I, FREDERICK WESTERBECK, a citizen of the United States of America, a resident of the city of St. Louis, 5 in the State of Missouri, have invented certain new and useful Improvements in Sheet-Metal Display Boxes, of which the following is a full, clear, and exact description, reference being had to the accompanying drawings, forming a part of this specification.

My invention relates to display boxes intended more particularly for holding and displaying bakery products, such as crackers and small cakes, and the display fronts of 15 which are provided with sight openings having transparent panels therein, and also with signs, usually indicating either, or both, the names of the manufacturers and the contents of the boxes. Such display boxes are 20 now commonly made with display fronts of brass or other metal which may be readily polished from time to time to provide an attractive and pleasing finish for the fronts of the boxes.

25 The transparent panels and the signs used in display boxes of the kind to which my invention relates have heretofore been removably mounted in the fronts of the boxes, as, for example, in the Letters Patent of the 30 United States No. 995,747, issued to me June 20, 1911. Heretofore, however, the signs have been merely slipped into guides or 35 pockets provided therefor, without any provision of means for so positioning the signs and holding them as to exclude the entrance of dust or other foreign matter.

The fronts of the boxes are necessarily weakened in forming sign and sight openings therein, and as a consequence it has 40 been found that when said fronts are polished they are too weak to withstand the pressure applied to them without bending the metal in the box fronts.

One of the objects of my present invention 45 is to provide a display box front with a sign-receiving opening, and a dished sign so held in said opening as to exclude the entrance of dirt or foreign matter around the sign to the interior of the box. A further object of the invention is to provide 50 means for so locking the sign as to force it tightly into the opening provided therefor. A

still further object of the invention is to provide a fastening device serving the dual function of retaining the transparent sight 55 panel and the sign. Another object of the invention is to provide means whereby the weak portion of the box front between the sign-receiving opening and the sight opening is so reinforced that it will effectually 60 withstand strain imposed thereagainst in the act of polishing the box front.

Fig. I is a front elevation, partly in vertical section, of my display box.

Fig. II is an enlarged vertical section 65 through the display front of my box.

Fig. III is an enlarged horizontal section taken through one of the front corners near the top of the box.

Fig. IV is an elevation of a fragment of 70 the box front, showing the fastening device for retaining the sight panel and the sign.

The body of my display box, aside from the box front and the features coexistent therewith, may be of any ordinary construction, including a bottom A, and side walls B. At the forward end of the bottom A is a vertical flange a and back of and parallel with said flange is a stop a' which is spaced 75 from said flange.

D designates the front of my display box as a whole, said front being secured to the bottom flange a and the side walls B. In the box front D in a sign plate opening 1 surrounded by a rearwardly extending marginal flange 2, preferably inclined from the vertical plane of the box front as seen most clearly in Figs. II and III. The box front also contains a sight opening 3 surrounded by a marginal flange 4 similar to the marginal flange surrounding the sign opening. 85

Between said openings 1 and 3 is a web 5 including in its structure portions of the flanges 2 and 4. For the purpose of reinforcing this web, which is the weakest portion of the box front, I dispose at the rear thereof stiffening strips 6 and 7 extending longitudinally of, and secured to, the web, and which also serve as holders for the sign and sight panels, as will hereinafter appear. 90 The stiffener strip 6 is of Z-shape in cross section and comprises a wing secured to the web 5, a horizontal ledge member extending rearwardly from said web, and an upstand- 95

ing rear wing 8 spaced from the portion of the flange 2 at the upper margin of the web 5. The stiffener strip 7 is of L-shape in cross section, the upper horizontal wing of said strip being secured to the ledge member of the strip 6 and the other wing extending downwardly substantially parallel with the web 5 of the box front into proximity with the upper edge of the sight opening 3. The 10 stiffener strips 6 and 7 are soldered or otherwise suitably fastened to the web 5, and by their presence very efficiently resist strain tending to bend or distort the web when it is polished.

15 E designates a sign exposed to view at the sight opening 1 in the box front D. This sign is of dished form to provide a central sign-receiving portion 9 extending through the sign-receiving opening 1, and 20 a marginal portion 10 surrounding said central portion and resting against the rearwardly extending flange 2 surrounding the opening 1. Upon the side walls B of the box body are rounded abutments 11, said 25 abutments being located above and slightly rearwardly from the portions of the marginal flanges 2 above the sign-receiving opening 1. When the sign E is to be put in place in the box front, its upper margin is 30 passed between the upper portion of the flange 2 adjacent the rounded abutments 11 in an inclined position and moved upwardly and then forwardly until the lower edge of the sign may be passed forwardly towards 35 the wing 8 of the stiffener 6 and then lowered in front of said wing so as to be held in position between the flange 2 and wing 8. The upper portion of the sign is thus tightly wedged against the upper portion of the 40 flange 2 due to the relative positions of the upper portion of said flange and said abutments 11. The lower portion of the sign is tightly wedged against the lower portion of the flange 2 at the bottom of the sign opening 1 by means to be hereinafter described.

45 12 designates a sight panel which closes the sight opening 3 by contacting with the flange 4 surrounding said opening. The upper edge of this sight panel extends into a 50 pocket back of the web 5 of the display front, and between it and the stiffener strip 7 and the lower edge of the panel is seated in front of the stop a' upon the bottom of the box after the panel has been passed over said stop from the position in which it is seen in dotted lines, Fig. II.

55 A fastening device F for securing the sign E and the sight panel D is mounted upon the stiffener strip 7. This fastening device is pivotally supported at 13 and comprises an arm 14 having a finger 15 which extends through an opening 7' in the stiffener strip 7 and overlies the upper edge of the sight panel 12 to restrain said panel 60 from vertical movement. The fastening de-

vice also comprises a yieldable arm 16, which terminates in a downturned finger 17 adapted to enter a forwardly inclined notch 8' formed in the wing 8 of the stiffener strip 6. When the fastening device F is swung 70 on its pivot, the finger 15 is moved through the opening 7' in the stiffener strip 7 and the arm 16 is sprung upwardly and then lowered, so that its finger 17 enters the inclined notch 8' and moves downwardly 75 therein to force the lower edge of the sign E against the lower portion of the flange 2 surrounding the sign-receiving opening 1. The sign is thereby tightly impinged against said flange, and being also held tightly 80 against the flange by the abutments 11 so closes the sign-receiving opening of the display front as to eliminate all possibility of entrance of dirt or other foreign matter through the said opening to the interior of 85 the box.

I claim:

1. A display box having a front provided with a display opening and a sign-receiving opening, a closure plate for said display opening, a sign-confining member on said front adjacent said sign, said sign-confining member having a notch therein inclined toward said sign, and a fastening device insertible into said inclined notch to press 95 against said sign and hold it firmly against the margin of the sign-receiving opening, and also to lock the closure plate to the box.

2. A display box having a front provided with a sign-receiving opening, and a sight 100 opening separated by an intervening web, a stiffening device fixedly secured to the back of and extending the length of said web, a sign fitted to said sign-receiving opening and entering into said stiffening device, and a sight panel fitted to said sight opening and entering into said stiffening device.

3. A display box having a front provided with a sign-receiving opening and a sight opening separated by an intervening web, 110 stiffening means for said web comprising a Z-shaped wing member secured to and extending the length of said web and an L-shaped member secured to and extending the length of said Z-shaped member. 115

4. A display box having a front provided with a sign-receiving opening bounded by a marginal rearwardly extending flange and a sight opening separated by an intervening web and bounded by a marginal rearwardly 120 extending flange, a stiffening device secured to the back of said web, said stiffening device having a free edge parallel with and spaced from the marginal flange of said sign-receiving opening, a sign in said opening between said marginal flange and said free edge, said stiffening device having another free edge parallel with and spaced from the marginal flange of the sight opening, a sight panel fitted in said sight-open- 125 130

ing between said marginal flange of the sight opening and the last mentioned free edge, and fastening means on said stiffener having a finger insertable between said first named stiffener edge and said sign to wedge 5 said sign in a confined position and also having a finger insertable through said second named stiffener edge and contacting with the upper edge of said sight panel so as to prevent vertical movement thereof. ¹⁰

In testimony that I claim the foregoing I hereunto affix my signature.

FREDERICK WESTERBECK.
